(57) **CLAIM**

The ornamental design for a top part of a spoon eating utensil, as shown and described.

DESCRIPTION

FIG. 1 is a left side perspective view of a top part of a spoon eating utensil showing my new design;

FIG. 2 is a first end view thereof;

FIG. 3 is a left side elevation view thereof;

FIG. 4 is a right side elevation view thereof;

FIG. 5 is a second end view thereof;

FIG. 6 is a bottom plan view thereof;

FIG. 7 is a top plan view thereof;

FIG. 8 is a bottom, and left side perspective view thereof; and, FIG. 9 is a top, left side perspective view thereof.

The handle of the spoon eating utensil is shown in broken lines for illustrative purposes only and forms no part of the claimed design.
